UNITED STATES PATENT OFFICE.

DAVID EDWARDS, OF NEW YORK, N. Y.

STEAM-TRAP.

SPECIFICATION forming part of Letters Patent No. 244,571, dated July 19, 1881.

Application filed June 9, 1881. (No model.)

To all whom it may concern:

Be it known that I, DAVID EDWARDS, a citizen of the United States, residing at New York, in the county of New York and State of New York, have invented new and useful Improvements in Steam-Traps, of which the following is a specification.

This invention consists in the combination, with the float and with the trap-valve, of a tube which extends from the lower portion of the float and connects directly with a horizontally-sliding valve having an escape-channel through it, so that the water resulting from the condensation of moisture in the float is always free to escape through said channel, no matter what the position of the valve may be, while at the same time the rising-and-falling motion of the float is not impeded by a stuffing-box. Also, in the combination, with the float, the stem of the float, and the trap-valve, of two oblique guides, whereby when the float sinks down the valve is pressed up against its seat by the weight of the float, and when the float rises the valve is opened. Further, in the combination, with the float, the stem of the float, the valve, and the oblique guides, of a ring to which said guides are secured, and which can be adjusted on the valve-chamber, so that the distance to which the valve is opened by the float can be regulated.

This invention is illustrated in the accompanying drawings, in which Figure 1 represents a sectional side view of my steam-trap. Fig. 2 is an inside elevation of the valve-chamber. Fig. 3 is a horizontal section in the plane $x x$, Fig. 1.

Similar letters indicate corresponding parts.

In the drawings, the letter A designates a box, which connects by a pipe, B, with the steam coil or cords.

C is the float, from the lower portion of which extends a tubular stem, D, which is screwed into a hole, a, in the side of the longitudinally-sliding valve E. (See Fig. 3.) The hole a communicates with a channel, b, extending out through the end of the valve.

F is the valve-chamber, which is provided with a circular flange, c, by means of which it can be secured to the box A, Fig. 1, and in the interior of this chamber is formed the valve-

seat d. From the valve-chamber extends a tubular nipple, e, into the box A, and to the inner end of this nipple is secured a ring, f, by means of a set-screw, g, whereby the ring can be adjusted for regulating the distance to which the valve is opened by the float. Across the opening in this ring extend two oblique guides, $h h'$, Fig. 3, and the stem D of the float passes between these guides. When the float sinks down its weight presses the stem D up against the guide h , and the valve E is held up against its seat; but when the float rises the stem D bears against the guide h' and the valve E is moved away from its seat or opened.

It will be seen from this description that in my steam-trap the water resulting from the condensation of moisture in the float is free to pass off through the tubular stem and the channel b in the valve, no matter what the position of the valve may be—that is, communication between the channel b and the float is never cut off, because the valve opens and closes by a longitudinal-sliding movement. At the same time the rising-and-falling motion of the float is not impeded by a stuffing-box, and no space is left for leakage of steam.

What I claim as new, and desire to secure by Letters Patent, is—

1. The sliding valve E, having the escape-channel b , in combination with the float and the tubular stem attached directly to the valve, and always in communication with the escape-channel therein irrespective of the position of the valve, substantially as described.

2. The combination, substantially as herein-before described, of the float, the stem of the float, the trap-valve, and the two oblique guides $h h'$.

3. The combination, substantially as herein-before described, of the float, the stem of the float, the trap-valve, the two oblique guides, and the adjustable ring f.

In testimony whereof I have hereunto set my hand and seal in the presence of two subscribing witnesses.

DAVID EDWARDS. [L. S.]
